CONTROL DEVICE FOR PRINTING ROLLERS
IN PRINTING MACHINES

Philibert Deck, Zurich, Switzerland

Application October 14, 1950, Serial No. 190,113
In France May 15, 1950

2 Claims. (Cl. 101—248)

1

The present invention relates to printing machines and especially to printing machines wherein in a web of sheet material to be printed on (fabric, paper, or the like) is fed between a central cylinder, and a number of printing rollers disposed circumferentially around, and applied under resilient pressure against said central cylinder. The printing rollers have a movement of rotation imparted to them and owing to their pressure application against the central cylinder, drive the latter in rotation in a reverse direction from their own, thereby feeding the web of material. The printing rollers each serve to print a pattern upon the web, and the individual patterns may—or may not—each comprise an individual colour. It is necessary that the various component patterns be printed so as to harmonize together in producing a predetermined general pattern, and this requires that an accurate relative setting be maintained between the printing rollers during a given printing operation.

In conventional machines of this type, the printing rollers are rotated by direct meshing engagement with a common gear wheel, and their adjustment for mutual registration of the printed patterns is generally accomplished by means of a manually-controlled worm adapted to rotate the hub of the printing roller in either direction. Manual operation of this worm involves risk of accident to personnel and damage to apparatus.

An object of the present invention is to provide a device for controlling the printing rollers in a printing machine of the type indicated, whereby the individual setting of each printing roller may be adjusted with flexibility, accuracy and safety.

The invention essentially consists of interposing in the control means for each printing roller a differential gearing, whereby any desired corrective adjustment may be imparted with great flexibility to each individual roller.

The features of the invention will appear from the ensuing description relating to one form of embodiment thereof selected by way of example, with reference to the accompanying drawings in which:

Fig. 1 is a general view in elevation of a printing machine according to the invention, and

Fig. 2 is a view on an enlarged scale in section on line II—II of Fig. 1.

The printing machine shown comprises a frame 1 supporting the shaft 2 of a central cylinder 3, and a number of sliding supports 4 are spaced peripherally of the central cylinder and each adapted to receive a carriage 5 slidable thereon,

each carriage 5 supporting through journals 6 the shaft 7 of printing roller 8.

In alignment with the shaft 2 is a separate shaft 2a which carries a freely rotatable central gear wheel 9 (Figs. 1 and 2) meshing with a drive pinion 10 secured on a shaft 11 driven from a motor, not shown. Pivoted freely on the end 12 of shaft 2a is a disc 13 formed with an elongated opening 14 through which the shaft 11 extends. The disc 13 moreover comprises an integral arm 15 projecting radially therefrom and formed at its outer end with a worm gear sector meshing with a worm 16. The shaft 17 of the worm is supported in bearings formed in a bracket 18 secured at 19 to the frame 1 and the shaft 17 carries at one of its ends a bevel pinion 20. The pinion 20 meshes with a further bevel pinion 21 mounted on a shaft 22 supported in a bearing 23 integral with the bracket 18. The shaft 22 may be controlled manually as with a crank, not illustrated, fitted into a square socket 24 formed on the shaft, or alternatively the shaft 22 may be controlled from an electric motor; any other suitable means may be used to control the shaft 22.

The disc 13 is provided, adjacent to the gears 25 carried on the shafts 7, with differential housings 26 serving as transmission means from the gear 9 to the gears 25, and motors 27 associated with the housings 26. Operation of the shaft 22 causes the disc 13 to be shifted from one to the other of two positions, namely a position in which the housings 26 are in engagement with the gears 25, and a disengaged position. In the embodiment illustrated, each motor 27 drives through a transmission (not shown), a worm gear 23 meshing with the gear teeth 29 of the planetary-carrier 30 of the differential gearing mounted on the shaft 31 supported at 32 on the housing 26. The planetary-carrier 30 carries planetaries 33 mounted on shafts 34 and two sun-gears 35 and 36. The sun-gear 35 is rigid with a bushing 37 mounted for rotation on shaft 34, a receiver pinion 38 being secured on said bushing. The sun-gear 36 is rigid with a further bushing 39 coaxial with 40 and rotatable around the bushing 37, and carries a transfer pinion 40 meshing with the gear 9. The shaft 31 and bushings 37 and 39 are rotatable relatively to one another, with a soft friction fit or with the interposal of ball bearings. In the 45 clutched position of disc 13, each receiver pinion 38 meshes with the gear 25 of the related printing roller.

The device operates as follows. The web of fabric or paper is inserted between cylinder 3 and the engraved printing rollers 8. The drive shaft

11 acting through pinion 10 drives the central gear 9, which meshes in turn with the pinions 40 carried in the housings 26 rigid with the disc. In each housing 26 the pinion 40 thus rotated rotates in turn the sun-gear 36 with which it is rigid, and the sun-gear 36 transmits through the medium of the planetaries 33 its rotation to the sun-gear 35 and thus to the pinion 38 integral therewith. In the engaged condition of disc 13, the pinions 38 mesh with the gears 25. In the disengaged condition of the disc, the pinions 38 are spaced away from the gears 25.

In the engaged position of the disc and with the motors 27 stopped, the gears 25 are all subjected to a bodily movement of rotation, and consequently the printing rollers 8 are all rotated at the same speed; the pressure exerted by them against the central cylinder 3 causes said cylinder to revolve in the opposite direction, thereby feeding the web.

It may occur in operation that one or more of the engraved printing rollers assume a lag or lead relatively to the pattern to be printed; the motor 27 relating to a roller thus displaced is then started in the requisite direction to counteract this displacement; rotation of this motor imparts through the medium of worm gear 28 a corresponding rotation to the planetary-carrier 30. This brings about, in known manner, an accelerated or retarded rotation of the planetaries 33, as the case may be, relatively to the rotation assumed by them with the motor 27 stopped.

The movement of the sun-gear 36 is therefore transmitted to the sun-gear 35 corrected one way or the other according to the movement imparted to the motor 27. The related printing roller thereby assumes a movement adapted to restore its correct setting relatively to the general pattern. The disc 13 carrying the differential gearings and their motors, may be shifted to a de-clutching position whereby the pinions 38 may be moved away from the pinions 25, thereby breaking the transmission path from the gear 9 to the printing rollers. Depending on the diameter of the printing roller, the pinion 25 may be formed with a number of gear-teeth bearing such a relation to said diameter that the central gear 9 will not have to be changed if the diameters of the printing rollers are altered.

It will be seen that the arrangement according to my invention makes it possible to correct in a particularly flexible and accurate manner any displacements that may occur during operation in the relative positions of one or more of the printing rollers.

The invention is not restricted to the specific form of construction illustrated and described, but should be construed as including any modifications in the various elements thereof which do not depart from the spirit and scope of the invention.

What I claim is:

1. A printing machine comprising a frame, a central cylinder journalled in said frame, a plurality of printing rollers peripherally engaging said cylinder and having gears disposed outwardly of said frame, a spindle coaxial with said cylinder and projecting outwardly from said frame, on the same side thereof as said gears, a toothed control wheel mounted on said spindle, a rotary disc mounted on said spindle outwardly of said wheel, casings supported by said disc and projecting inwardly therefrom, electric motors opposed to said casings respectively supported by the disc and extending outwardly therefrom, a fixed pin supported by and extending within each said casing parallelly to said spindle, two adjacent pinions mounted on said pin near the rotary disc and being in mesh with said wheel and with one of said printing roller gears, respectively, and a differential mechanism mounted on said pin inwardly from the pinions and having sun gears respectively connected to said pinions, a planetary carrier connected to one of said electric motors.
2. A printing machine comprising a frame, a central cylinder journalled in said frame, a plurality of printing rollers peripherally engaging said cylinder and having gears disposed outwardly of said frame, a spindle coaxial with said cylinder and projecting outwardly from said frame on the same side thereof as said gears, a toothed control wheel mounted on said spindle, a rotary disc mounted on said spindle outwardly of said wheel and having therein an opening circumferentially elongated, a control shaft passing through said opening, a control pinion mounted on said shaft and being in mesh with said wheel, casings supported by said disc and projecting inwardly therefrom, electric motors opposed to said casings respectively supported by the disc and extending outwardly therefrom, a fixed pin supported by and extending within each said casing parallelly to said spindle, two adjacent pinions mounted on said pin near the rotary disc and being in mesh with said wheel and with one of said printing roller gears, respectively, and a differential mechanism mounted on said pin inwardly from the pinions and having sun gears respectively connected to said pinions, a planetary carrier connected to one of said electric motors.

PHILIBERT DECK.
